UNITED STATES PATENT OFFICE.

CHARLES T. DICKEY, OF ELIZABETH, NEW JERSEY, ASSIGNOR TO JOHN J. VOORHEES, JR., OF JERSEY CITY, NEW JERSEY.

APPARATUS FOR PRODUCING WATERPROOF FELT.

1,315,763.

Specification of Letters Patent.

Patented Sept. 9, 1919.

Application filed July 23, 1915. Serial No. 41,475.

To all whom it may concern:

Be it known that I, CHARLES T. DICKEY, a citizen of the United States, residing at Elizabeth, in the county of Union and State 5 of New Jersey, have invented certain new and useful Improvements in Apparatus for Producing Waterproof Felt, of which the following, taken in connection with the accompanying drawings, is a full, clear, and 10 concise description thereof.

The present invention relates generally to improvements in waterproof fabrics and methods of producing the same and more specifically to a waterproof felt and the 15 production thereof.

Numerous unsuccessful attempts have been made to produce a satisfactory and serviceable waterproof felt, which could be employed as a substitute for leather in the 20 production of soles for shoes, in manufacturing suit cases, trunks and the like. All of these attempts have been unsuccessful by reason of the fact that the means employed for treating the felt have been 25 more or less complicated, making their use from an economic manufacturing standpoint impracticable. Furthermore, the resultant products of these methods have been found to be unsatisfactory in many respects for 30 the reason that the felt has lost its inherent characteristics to a considerable degree and did not possess the durability and the waterproof qualities, which are the strongest essentials of a satisfactory commercial product.

The primary object of the present invention is to overcome the disadvantages of the known methods of producing a waterproof felt and to provide a means, whereby the 35 felt may be treated in an expeditious and economical manner, so that it will retain all of its inherent characteristics, while at the same time, it will possess great durability and be absolutely impervious to moisture, thus rendering the product produced by my 40 invention adaptable for use as an efficient substitute for leather for all purposes, where practicable, and also enabling its employment for various other purposes where at present rubber, wood, cardboard and other 45 fabrics are now used.

A further object of my invention is to treat the felt or similar fabric by a vacuum process, wherein the various steps may be performed with despatch and the fabric im-

regnated with the waterproofing material 55 or compound, so that it will unite or commingle with the fibers of the fabric and become an integral part thereof, adding materially to the durability of the fabric and adapting it for use for a multiplicity of 60 purposes to which the unsatisfactory products heretofore referred to have been inapplicable.

Other objects and advantages of my invention, such as its simplicity of operation, 65 permitting the employment of practically unskilled labor, will become manifest as the description proceeds and I would have it understood that I do not limit myself to the precise details of structure illustrated or described, nor to the specific uses herein set forth, reserving to myself the full range of equivalents of my invention, to which I may be entitled in its broadest aspect.

I shall now proceed to describe my invention with reference to the accompanying drawings and then point out with more particularity, the essential elements of novelty 70 therein.

In the drawings,

Figure 1 is a plan view of the apparatus employed by me.

Fig. 2 is a side elevation partly in section of the structure shown in Fig. 1.

Fig. 3 represents a section of the fabric 85 or felt before treatment; and

Fig. 4 represents the fabric shown in Fig. 3 subsequent to waterproofing.

Referring now to the drawings in detail, in which like characters of reference are employed to designate similar parts throughout the several views, 7 represents a rectangular sheet of felt of approximately a quarter of an inch in thickness prior to its treatment by my improved process. A number of these sheets of raw felt 7 are placed within the container 8, the interior of which is provided with the preferably spirally arranged screen 9, supported from the annular band 10 mounted on the standards 11 provided with the foot or extended portions 12, which are rigidly secured to the ring 12^a to form a base resting upon the bottom of the container.

The convolutions of the spiral screen 9 105 are spaced apart, so as to receive the sheets of felt therebetween and maintain them out of contact with each other to facilitate the

efficient carrying out of my invention, as will hereinafter be manifest. When the felt has been positioned, as just explained, the container is hermetically sealed by means of 5 the lid or closure 13 hinged thereto at 14, which is locked in position by adjusting the securing or locking nuts 17 on the hinged clamping members 15, the shanks of the latter being seated within the recesses 16 provided on the edge of the periphery of said lid or closure 13.

The reference character 18 indicates a preferably cylindrical tank for containing the waterproofing material, preferably rubber, which is in a liquid state and of the proper consistency for obtaining the object of my invention in an efficient manner. Connected to the base of the tank 18 is an outlet pipe 19 having an elbow 20 communicating with the pipe 21 provided with the valve 22. The pipe 21, as will be observed, is coupled at 23 to one end of a pipe 24 provided with a valve 25 located in proximity to its other end, which latter end is connected 25 by a suitable coupling and elbow, shown at 26, to the interiorly threaded bore of the boss 27 formed on the closure or lid 13, the lower end of the coupling communicating with the interior of the container 8, as 30 shown in Fig. 1.

When the fabric has been placed within the container, the latter is hermetically sealed by means of the lid or closure 13, as previously explained, and a vacuum is created 35 within the container by the operation of an exhaust pump (not shown) connected by means of the pipe line 27 to the vacuum tank 28, the latter communicating with the interior of the container through the pipe line 29, which has a flexible connection 30 with the pipe 31 mounted on the closure or lid 13 and leading to the interior of the container as shown at 32 in Figs. 1 and 2, communication between the tank 28 and the container being controlled by the valve 29.

It is obvious that when the air has been exhausted from the container 8 and from the felt or fabric therein, interstices will exist between the fibers of the fabric, so 50 that when the valves 22 and 25 are opened to admit the waterproofing material to the interior of the container 8, these interstices will be filled, or in other words, the fabric will be thoroughly impregnated with the 55 waterproofing material, which will unite with and practically become an integral part thereof.

As the container is filled up by the waterproofing material, the latter backs up 60 through the pipe 31 and its connection through pipe 29, into the vacuum tank 28, the level of the material being visible within the gage glass 33. The valve 25 is thereupon closed and after a short period of time, 65 the flexible connection 30 is uncoupled from

the pipe 29 and coupled or connected to the pipe 34 provided with the valve 35, the pipe 34 communicating with a pump or compressor of any suitable type (not shown). The valve 36 in the pipe line 37 leading from the bottom of the container 8 and discharging into the tank 18 through the nozzle 38 is then opened, whereby the waterproofing material under the pressure of the pump or compressor is forced through the pipe line 75 37 back into the tank 18. When all of the waterproofing material has been thus removed from the container, any residue remaining is permitted to flow out through the pipe 39 by opening the valve 40 located therein, the residue in the tank 28 being similarly removed by opening the valve 41 carried by the pipe 42.

At the conclusion of the operation just described the flexible connection 30 is uncoupled from the pipe line 34 and the pipe 24 disconnected from the pipe 21, after which the lid or closure 13 is unlocked and thrown back upon its hinges in the direction of the arrow in Fig. 1. The impregnated fabric 90 may then be removed from within the convolutions of the screen after which pressure is applied thereto to compress the sheets to a thickness of approximately three-sixteenths of an inch, as shown in Fig. 4, when they 95 are submitted to a drying process. The sheets may then be packed for shipment or employed for such purposes as may be desired.

In carrying my invention into effect, any 100 suitable vulcanizing process may be used and any means which will operate satisfactorily may be employed for applying the requisite pressure to compress the sheets to the desired degree. As will be noted in the 105 embodiment shown, the tank 18, which contains the waterproofing material, is mounted in a plane above the top of the container 8, and is supported in any suitable manner, such as by means of beams 43, shown in Fig. 110

1. By this method, it is obvious that the waterproofing material will gravitate toward the interior of the container 8, when the valves 22 and 25 are opened, as heretofore explained. However, I do not limit myself to this particular arrangement, since, 115 it is apparent that the waterproofing material may be forced into the container under pressure and that the tank may be located in any desired position relative to the container; also, that the various components of my invention may be changed in details of structure and in their relative arrangement without departing from the spirit and scope 120 of my invention.

Having thus described my invention, what I claim as new herein and desire to secure by Letters Patent is:

1. In an apparatus for producing waterproof felt, the combination of a container 130

- having a spiral screen mounted therein, the convolutions of the spiral being supported, so as to be separated one from the other, to provide a support for the felt, means for 5 hermetically sealing the container, means for creating a vacuum therein and means for impregnating the felt with a water-proofing material in the vacuum within said container.
- 10 2. In an apparatus for water-proofing felt, the combination of a container, a spiral screen positioned therein, the convolutions of said screen being spaced apart whereby the sheets of felt to be treated will be separated, one from the other, means for hermetically sealing the container, a vacuum tank communicating with said container and adapted to function to create a vacuum within said container, a tank for the water-proofing material communicating with said container and means for controlling the admission of the water-proofing material to said container whereby the felt will be impregnated with said water-proofing material in 20 the vacuum within said container.
3. In an apparatus for water-proofing fabric, the combination of a container having a spirally-arranged screen located therein, the convolutions of the spiral being spaced apart whereby the fabric may be inserted therebetween, means for hermetically sealing the container, means for creating a vacuum within the container, means for supplying the water-proofing material 30 to the interior of the container and means for expelling the water-proofing material from the container under pressure.
4. In an apparatus for waterproofing felt, the combination of a container having a screen located therein, one portion of the screen being spaced apart from another whereby the fabric may be inserted therebetween, means for hermetically sealing the container, means for creating a vacuum within the container, means for admitting water-proofing material to the container, and 40 means for expelling the waterproofing material from the container under pressure.
5. In an apparatus for producing water-proof felt, the combination of a container, means for hermetically sealing said container, a plurality of partitions arranged within said container and adapted to support sheets of felt therein, whereby said sheets of felt will be spaced one from the other, means communicating with the interior of said container for exhausting the air therefrom to create a vacuum, whereby interstices will be formed between the fibers of the fabric, means for admitting a water-proofing material to the interior of said container for impregnating the fabric and means for withdrawing the water-proofing material from said container at the conclusion of the impregnating operation. 65
6. In an apparatus for producing water-proof felt, the combination of a container having a supporting device arranged therein, the parts thereof being so positioned relatively to each other as to receive and support 70 a plurality of sheets of felt within said container and out of contact with each other, means for hermetically sealing the container, means for creating a vacuum within the container, and means for impregnating the felt 75 with a water-proofing material while in the vacuum.
7. In an apparatus for producing water-proof felt, the combination of a container, means for hermetically sealing said container, a supporting device arranged within said container, said supporting device embodying a plurality of supporting surfaces spaced from each other and adapted to receive a plurality of sheets of felt so as to 80 maintain the individual sheets out of contact with each other, means for creating a vacuum in said container, and means for impregnating the felt with a water-proofing material while in the vacuum. 85

CHARLES T. DICKEY.
